US0D1089943S

(12) United States Design Patent (10) Patent No.: US D1,089,943 S
(45) Date of Patent: * Aug. 19, 2025

(54) COIN HOLDER

(71) Applicant: Shenzhen Microgravity Technology Co, Ltd., Shenzhen (CN)

(72) Inventor: Shuai Zhang, Shenzhen (CN)

() Term: 15 Years

(21) Appl. No.: 29/945,590

(22) Filed: Jun. 4, 2024

(51) LOC (15) Cl. 99-00

(52) U.S. Cl.

USPC D99/34

(58) Field of Classification Search

(57) CLAIM

The ornamental design for a coin holder as shown and described.

DESCRIPTION

FIG. 1 is a perspective view of a coin holder showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof

FIG. 8 is a bottom view thereof

FIG. 9 is an enlarged portion view taken from encircled portion labeled, "9," in FIG. 1; and,

FIG. 10 is an enlarged portion view taken from encircled portion labeled, "10," in FIG. 1.

The dash-dash broken lines in the drawings depict portions of the coin holder that form no part of the claimed design. The dot-dash broken lines represent boundaries of the enlarged portions and form no part of the claimed design.

1 Claim, 10 Drawing Sheets
